SPRING MATTRESS CONSTRUCTION

Nathan C. Goldberg, New York, N. Y.

Application July 8, 1949, Serial No. 103,617

3 Claims. (Cl. 5—267)

1

This invention is a novel spring mattress construction, being a class or type of structure commonly referred to in the art as an inner-spring mattress, falling within Class 5 Beds, subclass 351 Spring Mattresses.

Such a structure commonly comprises as its interior portion, a springy construction composed in great part of metal spring elements, including the conventional upright coil springs giving depth to the mattress, and including also at each of the upper and lower surfaces or metal fabrics of the mattress inner portion a series of members called ties, in the form of tiewires, having a general longitudinal arrangement; the end, or top and bottom, convolutions of the coil springs being in the upper and lower bounding planes of the mattress, and arranged so that each such end convolution falls between two of the tiewires or at least adjacent to one wire, the system as a whole thereby providing a large number of tie points at each of which a tiewire, which may be of cable form, is tied, as by a clip of plate or wire construction to at least one of the adjacent coil springs, usually to a pair of adjacent coil springs; these elements, and the numerous clips or other ties or connectors, providing the unitary spring-metal mattress interior portion. The metal elements at the upper plane or top surface of the spring structure may be considered a metal or spring fabric, and the same with the bottom elements. Another common element of a spring mattress inner structure is a peripheral wire or flexible element providing a rim for the metal fabric, top or bottom, and tied in with the coil springs, and tiewires, but this is optional with the present invention and may be omitted.

Such a spring mattress construction conventionally has also an outer portion or woven fabric cover which completely encloses the assemblage of interior elements, including the metal parts and commonly some padding material between the metal parts and cover; but the present invention is directed more particularly to the improvement of the interior metallic structure; wherefore the woven fabric covering needs but little illustration or description. A complete spring mattress may of course be practically used to overlie any type of bed bottom, referred to in Class 5 subclass 230 etc.; which bottom may be a spring bottom, conventionally known as a bed-spring, mountable upon the bed frame and giving support to the mattress; these two articles of manufacture, the underlying bedspring and the overlying spring mattress being distinctly different articles involving distinct problems and characteristics of structure and action. An instance of a bedspring is the prior patent Goldberg 2,382,990 of 1945 in subclass 267, while an instance of a spring mattress is the patent of Levine 2,197,131 of 1940 in subclass 273.

The general objects of the present invention are to afford a spring mattress construction of

2

improved efficiency and resiliency as well as strength and durability. A specific object is to improve, throughout the structure, the forms of the various component metal elements and their operation, and to provide for strong and permanent interconnections between the main elements, namely, the helical upright or coil springs and the tiewires; and, as another feature, to provide such interconnections in a manner to prevent practically any slippage, for example longitudinally as between the coil spring convolutions and the wires or tie-cables which extend longitudinally and are tied or clipped to the coil springs at the numerous tie points of the structure.

Other and further objects and advantages of the invention will be explained in the hereinafter following description of an embodiment of the invention or will be understood by those conversant with the subject. To the attainment of such objects and advantages the present invention consists in the novel spring mattress construction, and the novel cooperative elements and combinations comprised therein, and the mode of action thereof, illustrated by several examples in the accompanying description and drawings.

In the accompanying drawings, Fig. 1 may be considered as an example of a first form of the invention, shown as a top plan view of a partial area of a spring mattress construction; it being understood that in bottom view the fabric structure may be either identical with the top view, the mattress in such case being reversible, or may be of different construction; Fig. 1 showing a substantial area of the metal fabric, and a small area of the woven fabric of the mattress cover. For purposes of description herein the disclosure of the metal fabric and points of novelty may be treated as those of the top fabric, irrespective of the construction of the metallic bottom fabric of the complete spring mattress.

Fig. 2 is a side elevation of a portion of the metal structure of Fig. 1, comprising a plurality of the upright coil springs and the top and bottom fabrics of the structure; the top and bottom fabrics being slightly different.

Fig. 3 on a larger scale shows in expanded top view a portion of Fig. 1, in the neighborhood of a tie point, but with the connecting clip omitted, and the tiewire and adjacent coil springs shown separated away from each other.

Fig. 4 is a vertical section of a detail taken on the section line 4—4 of Fig. 2 extending through one of the tie points between a tiewire and adjacent coil springs.

Fig. 5 is a perspective view of one form of a connecting clip, of the plate variety, although various other forms of clip, whether plate clips or wire clips, are well known and are available for the purposes of this invention.

While the above described Figs. 1 to 5 disclose the first embodiment of the present invention; several other forms and modifications

thereof, having features in common with the first form, are shown in the remaining figures, wherein Fig. 6 shows a small area of a second form of spring fabric in plan view; while Fig. 7 is a detail of the plate clip arrangement taken in vertical section on the line 7—7 of Fig. 6.

Figs. 8, 9 and 10 are sectional views like Fig. 7 showing substitute ways of accommodating tie and coil wires in plate clips, adapted to be used in arrangements like those of Figs. 1, 6, 7 or 11.

Fig. 11 shows a third form in top view with the clip seen in section; a vertical cross section of which could correspond with any of Figs. 8, 9 and 10.

Fig. 12 in completed top view, and Fig. 13 before completion, show, as a fourth form, a wire clip produced from an offset loop of tiewire, in lieu of a plate clip, and usable with certain other illustrated forms.

Fig. 14 in top view like Fig. 6 or Fig. 11 shows as a fifth form a variation of plate clip arrangement, the clip shown in section.

Fig. 15 shows a sixth form, in plan view, wherein the adjacent coil spring convolutions are somewhat separated and out of tangency, with double-loop interconnections between coils and each loop formed from a common tiewire and clipped to one coil spring.

Fig. 16 in top view, and Fig. 17 is an enlarged sectional view through the clip show a seventh form embodying variations over Figs. 6, 11 and 14.

Fig. 18 in top view, and Fig. 19 in side elevation show an eighth form of spring mattress fabric wherein the upright coils are well separated from each other both transversely and longitudinally between coil rows, with special tiewires and with clips at the tie points, each clip tying but one coil to one tiewire.

Fig. 20 in top view, and Fig. 21 in elevation, and Fig. 22 in detail perspective, and Fig. 23 in section on line 23—23 of Fig. 21 shows a ninth form of the invention containing several modifications over other forms, and with plate clips shown at the tie points.

Fig. 24 is a top view like part of Fig. 20 showing modified features and the use of wrapped wire clips, as a tenth form.

The three sheets of drawings, by means of twenty-four figures show ten different forms of the invention, which is a spring mattress construction of the kind whose spring structure is of substantial depth due to the conventional system of upright coil springs that are arranged in longitudinal rows and in methodical transverse arrangements, between the top and bottom surfaces or spring fabrics of the structure. Taking up the different forms in succession these will be described as to additional conventional elements, arrangements and relations and various features of novelty of which the underlying features extend through all of the disclosed forms.

The first form of the invention is that shown on sheet 1 in Figs. 1 to 5, wherein the showing of the construction is confined to a few of the units, it being understood that the elements of the units may be extended to any desired length and width of spring mattress, with repetition of structure from unit to unit. The springy metal structure 30 as a whole is built up of the coil spring elements and certain tying elements which serve to interconnect the upright coil springs at interior points while a bounding or rim element serves similarly to tie

together and interconnect circumferentially the coil spring system, at both the upper and the lower surfaces or fabrics of the spring structure.

The metal or spring structure 30 is shown as comprising the conventional upright coil springs 31, positioned in longitudinal rows, extending from left to right in Figs. 1 and 2. Each coil spring, as usual, has a top end convolution 32 and a bottom end convolution 33; and in this form of the invention the end of the spring wire forming for example the top convolution is bent into a closing device or hitch 34, the wire end being bent centrally and twisted around the inner end of the top convolution, which is thus permanently closed into an approximate ring or circle. For gripping or tying purposes each end convolution may be formed with one or two or more offsets 35, each creating a small recess or bay taking part in the interconnections at each tie point. It is to be understood that in general the top and bottom spring fabrics are substantially alike, so that it is sufficient to describe the top fabric of the spring structure, the bottom structure being usually symmetrical similar thereto.

When the spring structure has been completely assembled and attached it forms a unitary metal interior 30, which however is not serviceable as a spring mattress without a woven fabric or other soft sheet material made in a size and shape to receive and snugly enclose the spring structure; and such a cover element 36 is shown in Figs. 1 and 2. There may also be the usual stuffing or matted or felted material interposed between the metal elements and the woven cover of the mattress, in a conventional way.

Referring further to the spring structure, there is shown a peripheral spring wire 37, constituting a rim wire or bounding element extending circumferentially around the entire structure and being attached by clips or devices 38 to the tangentially outer tie point of each of the peripheral coil springs, that is, to the top and bottom end convolutions of the coil springs; thus affording circumferential interconnection for the system of coil springs. The yieldable border wire 37 is characteristic, in spring mattresses, in having universal resilience.

Having thus described the coil springs and their peripheral interconnecting means or rim wire, it remains to describe the system of longitudinal tiewires 39 and 40, constituting parts of the top and bottom spring fabrics, and the interconnecting devices or clips by which the system of tiewires is interconnected in the structure, e. g. with the system of coil springs. As is conventional the illustrated tiewires run generally longitudinally, within the top and bottom fabrics, each tiewire extending adjacently to at least one row, and preferably two rows of coil spring end convolutions, the tiewires being clipped to such convolutions along a series of tangential tie points, thus affording interior interconnection for the system of coil springs. Such coil springs being thus interconnected efficiently both peripherally and interiorly the entire spring structure is effectively unified, constituting an article of manufacture adapted readily to be completed into a serviceable spring mattress by the addition of stuffing material and enclosing cover as described.

The longitudinal ends of the tiewires, whether these wires be built up of sections connected in tandem or be of continuously unitary character, may have their ends held or resiliently anchored,

at the two ends of the mattress, for example by reason of being fastened or clipped to the optional peripheral or border wires 37. In this way the complete interconnection of all of the metal parts of the mattress is afforded, with the required yield in every direction.

The spring structure thus indicated is characterized in that the longitudinal tiewires 39 and 40 are formed with definite zigzag stretches or areas 41 at each of a series of portions of the tiewire along its length, for example in the place or stretch, between each two of the tie points at which the tiewires are firmly clipped or bound to the end convolutions of the coil springs.

In reciting a zigzag portion or stretch of each generally longitudinal tiewire it is intended to refer to a wire portion manipulated and formed, as in a sinuate manner, into a series of cross folds or loops by the bending of the wire back and forth transversely to the general length, and in a manner to provide a substantially flat openwork area of substantial lateral width at each of these places; thereby enhancing the total supporting action given by the spring structure, and minimizing the presence of large unsupporting areas, while improving the lengthwise resilience of the tiewires and so increasing the general ability to yield. The load-supporting function is enhanced by the formation of a curved crowning of the zigzag area beyond the plane of the top convolutions, as will be further described.

Figs. 1 to 5 show a form wherein the widened area of the zigzag stretch 41 of tiewire, instead of being of uniform transverse extent, is shown of expanding then contracting width, this varying configuration giving effective advantages. Further, in said first form, the zigzag stretch, without departing from substantial flatness, is shown in Fig. 2 as of outwardly or upwardly arched or bowed contour, indicated at 47, thus enhancing the supporting function of the tiewire.

In the first form of the invention, further, it is seen that the tiewires 39 are formed with a few wavy crimps 42 at the tie points whereat the binding clips 44 are applied to attach the tiewires to the coil spring end convolutions 32. These clips are of the plate or band type and they cooperate to tie rigidly together the tiewire 39 and the adjacent tangential parts of the end convolutions 32, in which tying action the offset recesses 35 of the latter partake. The clips are tightly wrapped or wound as in Fig. 4, and each clip constricts the three elements into firm union. The crimped stretch 42 is shown symmetrical, as in Figs. 3 and 11, but could be unsymmetrical as shown at 42a in Figs. 6 and 14.

In referring to clips or binders, well known elements per se, the reference includes equivalents, functioning to attach and firmly connect, preferably by rigidly binding them together, a pair or several elongated elements, wires, convolutions and the like. While Figs. 1 to 5 show the wrapped band or plate type of clip, the wire type is elsewhere shown as in Figs. 12 and 13 wherein a part of the tiewire is diverted or offset to provide the clipping material; Figs. 15, 18 and 24 showing separate forms of wire clip. Mutual attachment by soldering or fuse-welding may sometimes be used, particularly between the clip and tiewire, leaving swinging play between clip and coil spring.

The clips 44 shown in the first form and others are plate clips, best shown in detail in Figs. 4 and 5, each clip having a body portion 45 with ex-

tended wings or ends 46 to be engaged to encircle or become wound around the juxtaposed tiewire and one or two coil springs; if two adjacent end convolutions are embraced in the clip, this renders the convolutions substantially tangent to each other, as seen in Fig. 1, the tiewire passing longitudinally through the point of tangency. The clips may be applied in various ways, for example as seen in Fig. 4, to embrace the wires to be clipped together, with the ends of the clip wings tucked inwardly and forcibly driven between the offsets 35, using well known bending methods and machinery, in a manner to leave the parts tightly engaged in their connecting and locking position. In referring to tiewires it is to be understood that any equivalent members may be used such as relatively stiff wire cables. Ordinarily such wires have no tensional yield to speak of, but with the zigzag areas 41 introduced this permits longitudinal yield under vertical pressure.

The manner in which the coil springs and tiewires are combined and locked to each other prevents longitudinal slip, which advantage is aided by the inclusion in the tiewires of the wavy stretches or crimps 42. The upright coil springs, the height of which gives the depth to the mattress, may be of any conventional type, the drawings indicating the double spiral-helix type of spring, having its maximum convolutions at its top and bottom ends. Each of the longitudinal tiewires traverses the several tie points in each longitudinal line between coil tops; and it is in the spaces between the tie points of tangency that the zigzag areas are formed, although there may also be a zigzag conformation to each tiewire as well as at the tiepoints. In any case the zigzag structure may be considered as one wherein there are successive offsets or bends in the tiewire reaching horizontally in both directions from the longitudinal center line of the tiewire. Each tiewire zigzag area may remain truly flat and horizontal in normal position, or the same may be normally somewhat crowned or pre-arched for the purposes already explained. In Fig. 2 only the topmost tiewire 39 is shown to be bowed or arched, at 47; but as shown in Fig. 21 the bottom tiewire also may be symmetrically arched at 48, in an inverted manner.

Referring further to the wavy stretches of tiewire, comprising several crimps 42, these crimps serve to strengthen the relative locating of the tiewire and the coil convolutions; and there may be only a pair of several such crimps. Figs. 1 and 3 show a triple crimp 42, but a double crimp may suffice. To improve the locking action between coil convolutions and tiewire crimps, the latter may be extended to such an extent, laterally beyond each end of the clip, as to form a positive stop against longitudinal slippage; and while this is not shown in Figs. 1 to 5, the principle is shown in Figs. 6, 11 and 14. A total of only two crimps may obviously be arranged to afford this locking action. Another useful function of the tiewire crimps 42 of Figs. 1 to 5 and analogous structures in other figures is as follows. It is desirable not merely to prevent each tiewire sliding longitudinally through the tie points but to prevent also any turning of the tiewire for the reason that such turning would disturb the desired flatwise position, or the arched position, of the zigzag area of the tiewire. This object is attained by reason of the presence in the tiewire of those of the crimps 42 which are contained in and encircled by the clip 44. As shown there will be

two crimps locked inside of the clip, and thus the tiewire is held against rotation, so that its zigzag construction and area will remain in its intended position.

The first form (Figs. 1-5) and the second form (Figs. 6-7) are partly the same but differ as follows. In the second form the tiewire crimps 42 at the exterior are unsymmetrically formed, whereas those in the first form are symmetrical, see Figs. 1 and 3. In the second form, but not in the first form, these crimps extend laterally beyond the clip, thereby providing stops against any longitudinal displacement of the tiewire relative to the clip. As another difference, the second form does not have the first form feature of tiewire crimps embraced by the clips, so that when the clips are wrapped and tightened they clamp securely the tiewire against turning or rotating, thus functioning to maintain flatwise the zigzag tiewire areas and prevent the tilting thereof away from the illustrated normal position. In other words the first form shows only one of the two displacement-preventing arrangements, the clamping against rotation, while the second form contains only the prevention of sliding, relying on grip to prevent tilt.

Referring to the second form Fig. 7 sectionally shows the arrangement within the plate metal clip 44. The tiewire 39 between the exterior crimps 42 extends straightly through the closed clip, e. g. above the two top convolutions 32, which thus can be at the same level. Adjacent on the drawing are shown three other arrangements of clip in Figs. 8, 9 and 10, being some of the many variations possible. It is to be understood that metal working machinery is well able to handle the manipulation of each clip in forcibly pressing and clamping it into its permanent holding position, and thus tying together the systems of convolutions and tiewires. Fig. 5 shows the clip 44 partly bent and adapted to be assembled as in Fig. 4 or as in any of Figs. 7 to 10; see also later Figs. 11, 12, 14, 17, 23 and 24 for other clipping details.

One effective manner of closing the clip is as shown in Figs. 4, 7 and 9, wherein the two wings of the clip are thrust and tucked inwardly between the tangential parts of two adjacent end convolutions of the coil springs. In Fig. 10 this plan is carried further in that the clip body 45 is elongated, and the wings are bent further so that each wing substantially encloses a convolution, and these convolutions are thus spaced well apart. In some of this group of figures the interior crimps 42 are shown as confined and clamped by the clip; but since clips of this kind can be effectively tightened for clamping purposes it is sometimes possible to omit the crimps and rely on the clips to hold the parts in relative position; for example in Figs. 16 and 17 the tiewires 39, pass undeflected through the tie points, between the zigzag areas 41.

Another variation of arrangement is that shown in Fig. 11 wherein the tiewire crimps 42 are symmetrically disposed contrary to Fig. 6 but having a lateral extension sufficient to cooperate with the clip to prevent longitudinal sliding, contrary to the first form of Figs. 1-5; and like both the first and fifth forms having interior tiewire crimps acting to prevent rotary displacement. Figs. 12 and 13 show a special fourth form to be described later. Fig. 14 shows a fifth form which follows Fig. 6 to a considerable extent, but wherein the tiewire, while having a wavy or zigzag form at the tiepoint, extends

longitudinally from tiepoint to tiepoint without the intermediate areas of zigzag bendings of substantial transverse extent improving the functions of resilience and load support.

- 5 Referring next to the fourth form as shown in Figs. 12 and 13, this has to do with the employment of a wire clip or binding device as distinguished from the plate clip shown in various figures; and especially has to do with a particular 10 construction of wire clip for clipping together one or a pair of coil spring convolutions with the tiewire extending through each tiepoint. Wire clips per se are well known and a simple form thereof is indicated in the lower part of Fig. 18. 15 That which is shown in Figs. 12 and 13 however is of special character, particularly in its use in interconnecting the elements of the spring structure by means of tiewires when the latter are formed with zigzag widened areas of the character hereinabove disclosed, these zigzag areas each being located between two consecutive tie points. Fig. 12 shows the adjacent convolutions 32 interconnected by the wire clip 49, which clip is constituted of an integral stretch of the 20 tiewire 39 itself. This length or stretch of tiewire is bent to shape and then wound around the convolutions, thus tying together the convolutions and at the same time tying the two of them to the tiewire 39. In general the center line of 25 the tiewire 39 extends through each tie point in a location substantially tangent to the convolutions, but a predetermined length of the tiewire is first bent to shape and then wound into place. Fig. 13 shows the first step of formation, the 30 wire being bent as a lateral V-loop, constituting an integral offset from the central portion of the tiewire. When the tiewire, at each tie point, is in proper position relative to the convolutions, it is then simply wound around, for more 35 than one turn and preferably for about two turns, and pressed into permanent-holding relation, the flared shape of the V-loop or offset 50 causing the wire to be laid in its gripping position without overlapping itself.
- 40 The sixth form is shown in Fig. 15, this having a unitary tiewire 39 with a series of zigzag supporting areas 41 and with successive tie points between the zigzag areas. This embodiment is available when there are parallel rows of end convolutions and it is desired to keep the convolutions out of contact and well spaced apart, as shown. This may be accomplished by bending a part of the tiewire at each tie point, in this case at a double tie point, into a double hook or 45 loop formation 52, with one end or hook of this device extending toward a convolution in a near row, the complementary end extending to the next row beyond. Such a double hook 52 preferably has the shape known as a pothook, each thereof affording double tie points and being an effective manner of embodying the present invention in such an arrangement. Each pothook 52 extends in one sense between the two opposite convolutions, linking them together, and in another sense it is interposed between two straight stretches 39 of tiewire, and this combined device 39, 52 being interposed between two zigzag areas 41, all of the same tiewire. For 50 interconnecting each tiewire, or its pothook, to the two adjacent rows of convolutions there are indicated a number of simple clips, in this case being wound clips of wire, each clip connecting one hook end of one pothook 52 to one adjacent convolution 32.
- 55 The seventh form of the invention, shown in 56

Figs. 16 and 17 are hereinabove partly referred to, is related to some of the preceding forms, such as that of Fig. 6, and having plate clips 44 like several preceding forms but having no offset crimps in the tiewires 39 at or near the tie point, relying upon the gripping function of the clips to hold together the opposite convolutions 32 and the tiewire passing through each tie point. In the seventh form also the convolutions are without the slight offsets 35 used to accommodate the clips and prevent displacement thereof upon the convolutions. In the seventh form are shown the zigzag areas 41 between the tie points, but no offsetting of the tiewire between these areas. The clip 44 is of the plate type, and may be like the clips shown in Figs. 4 to 10 or others, each clip interconnecting the two convolutions and the tiewire. Instead of the forms shown in Fig. 10 the clip of Figs. 16 and 17 may be of circular form as indicated at 54 in Fig. 17, the clip containing the two convolutions 32 superimposed above the straight tiewire 39.

The eighth form of the invention, partly derived from the sixth form of Fig. 15, is shown in Figs. 18 and 19. Again there are shown parallel longitudinal rows of end convolutions 32, parts of three such rows being shown. The alternate rows are offset to a suitable extent to cooperate with the illustrated tiewires and clips. The convolutions in each row are spaced apart longitudinally as is customary, and in this embodiment the successive rows also are spaced apart transversely to a substantial extent, this arrangement leaving a fairly wide space running longitudinally between any two adjacent rows. This space is utilized herein to accommodate a special form of tiewire with zigzag features. Thus, between each two convolution rows is shown a longitudinal tiewire 56, which is of zigzag formation at and adjacent to the tie points and preferably, as shown, for its full length. In other words Fig. 18 shows each tiewire 56 to be of zigzag or sinuous formation, with transverse loopings, throughout the length of the tiewire, this plan materially simplifying and cheapening the manufacture of the spring structure.

By the thus described eighth form of the invention the continuously looped tiewire, while clipped to the convolutions of both rows, is not, at any particular tie point, clipped to convolutions of the two rows. Moreover, each convolution, while clipped at two points is, at each point, clipped only to a single element, the interposed tiewire. In other words, each clip of this structure clips together just one convolution and just one tiewire loop. Thus, taking any single convolution, this is shown tied by a clip 44 to a front loop of tiewire, and by a separate clip 44 to a back loop of tiewire; and this construction gives complete interconnection between the system of convolutions and the system of tiewires, in affording a unitary spring structure for mattresses. Instead of the plate clips 44 shown and mentioned the loops of the tiewires 56 may be clipped to the convolutions by means of wire clips 53, as indicated in the near portion of Fig. 18.

In the eighth form of the invention thus described all of the top convolutions 32 and all of the zigzag tiewires 56 may be in the same top plane of the spring structure, and the same with the corresponding elements at the bottom thereof. On the other hand, to provide an improved supporting structure each of the zigzag tiewires 75

may be arched in those portions of its general length which lie between successive tie points; and this structure is indicated in the elevation view Fig. 19 wherein in full lines is shown a continuous zigzag tiewire 56, arched or crowned at 47 between tiepoints analogously to the corresponding showing in Figs. 2 and 21, and in dotted lines the next arch beyond.

The ninth form of disclosure is shown in Figs. 20 to 23 and the structure will be seen to resemble in a general way the corresponding structure of the first form in Figs. 1 to 5 although with extensive features of difference. The ninth form introduces the additional conception of employing tiewires which are sectional, or built up of separate lengths or links, as distinguished from those consisting of a unitary continuous and integral wire as is illustrated in the preceding figures. The upright coil springs 34 may be generally conventional each with a top convolution 32 and a bottom convolution 33; although these coil springs are of special construction and cooperation in the total structure. The structure also embodies, at the several tie points conventional clips 44, shown as plate clips, one at each tie point, tying one or preferably two coil spring convolutions to the adjacent tiewire, in this case sectional or discontinuous portions of tiewire.

The skeleton view, Fig. 22, shows that at the top each coil spring, beyond the completion of its circular form, carries a curved extension 59 which extends to the tangential tie point or clip 44, and thence beyond the clip as a straight tangential extension 59. This portion 59 is a true part of the tiewire, while the curved extension 58 is part of the coil spring but merging into the tiewire portion 59. To complete on Fig. 22 the description of one unit or section of the tiewire, beyond the straight portion or stretch 59, to the left, the tiewire extends to where it is shaped into zigzag form, at the area 68, and therebeyond, leftwardly again, through a straight tangential length 61 which ends in a lefthand terminus 62. These directional terms are relative but serve to convey a simpler description of the structure. From Fig. 22 are omitted the clips and all parts other than the integral tiewire sections, top and bottom, and the coil spring 34 with its top and bottom convolutions 32 and 33. Since the top and bottom portions are preferably identical the remainder of the description will be confined to the top convolutions and the top tiewires of the total structure.

Referring next to the top view, Fig. 20, and the side elevation, Fig. 21, the arrangements described on Fig. 22 are seen to be further illustrated. Starting at the righthand end of Figs. 20 and 21, it is first seen that the particular feature of disclosure pertains to the far side of each top convolution 32, 58, and while the clip 44 at each such point of tangency is seen to accommodate not only the far portion 58 or 59 of the near convolution, but the near portion 32 of the next convolution of the row beyond. This latter inclusion is for utilizing the clip to tie together the tangential pair of convolutions, but the portions therof which take part in the building up of the tiewire are not at the near side but are at the far side of each convolution. With this understood, the parts and relations providing the tiewires may be further explained, taking for discussion the tie point and clip 44 which are at the far side of the most righthand one of the three complete coil spring top convolutions 32, 58. For convenience of description the three coil

11

springs 31 that are fully shown in Figs. 20 and 21, which may be called front coil springs, are identified by the letters A, B and C placed near the centers thereof, it being understood that other identical ones, not shown, are assumed to exist further rightwardly, and also further leftwardly, from the three so marked; while further beyond are three rear coil springs in the next row, correspondingly marked A', B' and C'.

With attention directed first to the coil spring A and to Figs. 20, 21 and 22, each top convolution 32 is extended as the curved portion 58, which passes leftwardly tangentially into the clip 44, located at the tie point, or merging point, the same wire merging leftwardly as integral straight portion 59 tangent to the convolutions of springs A and A'. Integrally to the left the same wire portion 59 is continued as the shaped or zigzag portion or area 60 and therebeyond as the straight tangential portion 61 extending through clip 44 between coil springs B and B'; the final terminus 62 ending the integrally continued portions comprising a complete section 59, 60, 61 of the total tiewire.

Each clip 44, for example the one between coils B and B', thus contains, as Fig. 23 shows, first, the left end portion 61 of the tiewire section that issues from coil A, second, the straight tangential portion 59 that issues from coil B, and third, a small part of the top convolution 32 of the next coil spring B' to the rear. And with these the underneath part of the top front convolution, i. e., the part below the merger of 58, 59, may be contained within the clip thereto to hold more steadily, at top and bottom, the upright coil spring.

The longitudinal series of sections 59—60—61 that make up each tiewire are interconnected in endwise relation, each section at each of its ends being connected or clipped to an aligned section, so that each section at its ends enters two clips or clamps, while each clip or connector ties two section ends together. Each tiewire section originates just ahead of one clip and terminates just beyond the next clip. At the same time each clip is available to clip one or two coil spring tops to these connected tiewires, either by entry of convolutions into the clips or by the integral merging of the wire of a convolution with that of a tiewire.

In this way each complete tiewire consists of a number of sections in tandem, extending the full length of the mattress spring structure, and with the extreme longitudinal ends preferably clip connected with the end portions of the border wires 37, when used. Each such sectional tiewire is thus interconnected with the entire row of coil spring top convolutions to the front of and to the rear of the tiewire, providing a unitary spring structure with all parts interconnected at the tie points. Each tiewire is thus longitudinally built up by an extended number of sections or links which are joined to each other in tandem; the joining means in the disclosed embodiment being the clips 44, at the tie points, each such clip enclosing and gripping the second or left-hand end of one tiewire section and alongside it the first or righthand end of the next section to the left. The interconnection of the tiewire sections is thus rigid, by reason of the form of the attachments or clips, whereas in some cases a pivotal interconnection could serve. An advantage of the rigid connection is that each of these clips can be made to contain not only the first end of one section and the second end of the

12

preceding section, but also a portion of the tangentially adjacent convolution of the coil spring next to the rear. The disclosed arrangement of rendering the inception of each tiewire section an integral extension of the coil spring top convolution has certain advantages in the total structure, the last portion of the convolution merging into the first portion of the section; but this integrality between convolution and section could be omitted by extending the two separately into each clip. Each tiewire section traverses, at its first and second ends, two of the clips 44, while each of those clips also contains the end of the next lengthwise adjacent section, thus mechanically attaching together in tandem all of the tiewire sections. These explanations are thought to complete an understandable description of the ninth form of the invention contained in Figs. 20 to 23. On Fig. 20 one of the clips 44 is shown in its preclosed position, showing how the curved extension 58 of each top convolution 32 is passed into the clip, whereat it merges with the issuing straight portion 59 of the tiewire. The construction illustrated by these figures may have its tiewire portions 59, 60, 61, which extend integrally between tie points, formed with an upwardly crowned or arched arrangement 47, as best seen in Fig. 21, this being on the principles and for the purposes explained in connection with the similar arching structure 47 of Fig. 2.

As Fig. 23 shows, the clip 44 at each tie point embraces portions of the following, (1) the first straight portion 59 of one tiewire where it merges with the last curved portion of the front coil convolution, (2) the last straight portion 61 of the preceding tiewire, these two tiewires thus being clamped together in tandem, and (3) a portion of the opposite top convolution 23 of one of the rear coil springs; and additionally, not shown, it may be desirable to include with the merged portions 58 and 59, (4) the other end of the front top convolution 23, thus stabilizing such top convolution.

The final or tenth form seen in Fig. 24 is a modification of the ninth form. The plate clips 44 are replaced by wound wire clips 64, each enclosing, as before, a combined tiewire and convolution portion 58, 59 and the front portion of the convolution of the next coil spring to the rear. However, in this case, preferably, the clip does not enclose the left end of a tiewire extension piece 61, since this extension piece, instead of traversing a clip and terminating to the left of it is actually made use of to provide the wound wire clip 64. In this way the left end of each tiewire section, without the need of separate clips, is combined and tied in with the enclosed elements 59 and 32. Following the successive portions 59, 60 and 61 of each tiewire, the terminal or left end thereof is wrapped into three turns of a compact helix, constituting the clip, beyond which to the left extent the tiewire portions 59, 60 and 61, with the last mentioned again wrapped, at the next tie point, to clip together these parts and a short length of the top convolution 32 of the next coil spring to the rear.

The intermittently arched sections of the continuous element or tiewire, as shown at 41, 47 in Figs. 2, 19, 21, provide an integral preformed spring element adapted for use in a sprung article, such as a bed mattress; wherein the wire element is in tandem sections each arched upwardly or outwardly, and each arch containing a

zigzag construction of the wire affording a substantial load-supporting function; the tiewire portions between the convex arches being adapted to be mounted upon, for example clipped or secured to, some other elements of the spring structure.

Among other variations of mattress spring structure are the following forms. The coil spring rows may be differentially treated. Assuming twelve longitudinal rows across the total width, a middle group, as of six, may be interconnected by tiewires having zigzag areas as hereinabove described, while the side groups have plain prior-art type of tiewires. The invention is thus embodied where most needed and economy is effected elsewhere.

In another form the longitudinal rows of coil springs may be tied together by old or new tiewire types, conventional or novel, and running longitudinally between the coil-spring rows; but this system being supplemented by overlying special tiewires arranged longitudinally between the regular ones and crossing the diameters of the coil spring top convolutions in each row or in selected rows; and tied or clipped to the convolutions at the tie or crossing points; each such special tiewire being shaped with zigzag areas either confined to locations between coil spring convolutions or to the circular spaces inside the convolutions, or else of the full tiewire length. Any of such special tiewire arrangements may have their zigzag areas also arched to increase the springy supporting area of the entire structure.

Or, the preceding disclosure may be converted, or supplemented further, by arranging diametrically crossing tiewires transverse to the regular and special tiewires just described, thus additionally tying each of the coil spring longitudinal rows to the others thereof and providing further and zigzag supporting areas.

Still another variation relates more especially to an improvement in the mattress spring structure when its elements are held together by metal clips of the plate variety, such as the clips 44 in forms 1, 2, 3, 5, 7, 8 and 9. In illustrating these forms various expedients, such as the disclosed crimps 42, were illustrated for the purpose of performing one or both of the following functions: To prevent each tiewire, as a whole or when in sections, from sliding or becoming displaced longitudinally with respect to each tie point, each clip being located at a tie point; and to prevent each tiewire from turning or rotating within the clips, and thereby holding each area 41 of zigzag against tilting away from its desired flatwise position. In the variation in discussion both of these functions are attained by an improvement in the construction of the plate clip per se and in relation to the tiewire or tiewire portion traversing the clip. By this modified arrangement the tiewire need not have a series of crimps 42, and need not have any crimps longitudinally outside of the clip, and inside of the clip need have no more than a single crimp, this being a V-shaped offset or crimp located within the clip and between opposite sides of the clip, so that when the clip is forced and squeezed to its gripping condition, upon the tiewire and upon the coil spring convolutions that are also contained within the clip, these parts will become rigidly consolidated, the gripping of the V-crimp holding the tiewire against rotation, and effectively holding it also against endwise sliding displacement.

There have thus been disclosed a number of different embodiments of a spring mattress construction, or the spring structure thereof, embodying the principles and attaining the objects of the present invention; but as various matters of construction, combination and detail may be variously modified without departing from the principles involved it is not intended to limit the invention to such matters except to the extent set forth in the appended claims.

What is claimed is:

1. A spring mattress construction the spring structure of which comprises a system of upright coil springs arranged in longitudinal rows and formed with top and bottom end convolutions, and a system of longitudinal tiewires located substantially in the plane of end convolutions of the coil springs, and each longitudinal tiewire extending adjacently between two rows of such end convolutions and being clipped by a series of clips thereto along a longitudinal series of tie points; said spring structure being characterized in that each of said longitudinal tiewires is formed with widened areas each consisting of zigzag bendings of substantial transverse extent, and each constituting a generally horizontal open-work load-supporting area of tiewire midway between the coil springs, and said tiewire having crimps to provide a laterally offset portion which seats the clip therein, and said clip being arranged to hold said last-named offset portion firmly against the adjacent end convolutions of the upright coil springs in a way to prevent rotation of the tiewire, each portion of the tiewire having its zigzag area arched upwardly between the convolutions of successive coil springs thereby to produce a curved structural arch adapted to receive and support a substantial part of the load on the mattress.

2. A spring mattress construction as in claim 1 and wherein the crimped tiewire at each tie point has its crimps wholly contained within and cooperating with the clip thereat, thereby to prevent twisting of tiewire; and means to prevent displacement of each tiewire relative to the convolutions.

3. A structure as in claim 1 and wherein the tiewire has crimps extending laterally beyond and exteriorly of the clip to engage the edge of the clip thereby serving to prevent longitudinal displacement.

NATHAN C. GOLDBERG.
